YARN CARRIER ROD OPERATING MEANS
FOR STRAIGHT KNITTING MACHINESGottlob Bitzer, Lincoln Park, Pa., assignor to
Textile Machine Works, Wyomissing, Pa., a
corporation of Pennsylvania

Application March 27, 1942, Serial No. 436,414

21 Claims. (Cl. 66—127)

This invention relates to straight or full-fashioned knitting machines, and more particularly to means for determinedly controlling the action of certain selective yarn feeding mechanisms of such machines.

It is now common practice to knit full-fashioned hosiery according to the "ringless" principle, that is, with a plurality of yarns, usually three. For this purpose it is common practice to provide a friction box arrangement having automatic yarn carrier rod selector means for connecting and releasing the multiple yarn laying rods carrying out the "ringless" knitting. However, when knitting certain areas of a ringless stocking blank, only a single yarn is employed, and for this purpose a standard friction box of the full-fashioned knitting machine is ordinarily utilized to reciprocate a single yarn carrier bar. During operation of the single thread carrier, the "ringless" friction box is released from operation, and is disconnected from the friction rod of the machine so that the therewith associated carrier rod connecting and releasing, or selector means, can be moved to inactive position relative to the yarn carrier rods.

When the automatic carrier selecting mechanism for "ringless" knitting is put into operation, after a single rod has been operated as explained, the carrier rod connecting means associated with the friction box, must be precisely positioned for engagement with the first cooperating yarn carrier rod to be driven to lay the yarn for the initial course of the "ringless" portion. Certain automatic carrier selecting mechanisms heretofore available have proven unreliable and unsatisfactory in this respect in that their initial connection with the thread carrier bar was not effected as intended, with the result that the fabric was pressed off.

One object of my invention is to provide novel means in straight or full-fashioned knitting machines for overcoming the mentioned and other difficulties.

Another object is to provide such means which will invariably function to operate only the proper yarn carrier rod at the start of the "ringless" yarn laying cycle.

It is also an object of my invention to provide such means which will prevent moving of a selector into engaging position with the first carrier to be operated when the selector mechanism is improperly set.

A further object is to provide such means whereby only a certain one of the selectors can

be moved to engagement with its cooperating carrier at the start of the "ringless" cycle.

An additional object is to provide such means whereby engagement of the "ringless" yarn laying attachment with the friction rod of the machine cannot be effected when the proper carrier rod selector and its cooperating carrier rod are not in engaging position at the start of the "ringless" cycle.

With these and other objects in view which will become apparent from the following detailed description of the illustrative embodiments of the invention shown in the accompanying drawings, my invention resides in the yarn carrier rod operating mechanism comprising the novel elements, features of construction and arrangement of parts in cooperative relationship, as herein-after more particularly pointed out in the claims.

In the drawings:

20 Fig. 1 is a top plan view of a full-fashioned knitting machine with a portion of the length omitted as indicated by the section breaks and having one form of my invention applied thereto;

25 Fig. 2 is a front elevational view of the carrier rod driving mechanism shown at the center of Fig. 1 and enlarged relative thereto;

Fig. 3 is a cross sectional view taken substantially along the line 3—3 of Fig. 2;

30 Fig. 4 is a view similar to Fig. 3, but with the parts in different relative positions;

Fig. 5 is a cross sectional view taken substantially along the line 5—5 of Fig. 2;

Fig. 6 is a side view of the mechanism of Fig. 2 as seen from the left thereof;

35 Fig. 7 is a view similar to Fig. 6 but with parts in different relative positions;

Fig. 8 is a view of certain of the mechanism shown in Figs. 6 and 7, but shown in different relative positions;

40 Fig. 9 is a sectional view taken substantially along the line 9—9 of Fig. 1;

Fig. 10 is a cross sectional view taken substantially along the line 10—10 of Fig. 2;

Fig. 11 is a cross sectional view taken substantially along the line 11—11 of Fig. 10;

Fig. 12 is a sectional view taken substantially along the line 12—12 of Fig. 11;

Fig. 13 is a sectional view taken along the line 13—13 of Fig. 1 and turned at right angles relative thereto;

Fig. 14 is a diagrammatic plan view of certain of the carrier rods and driving means therefor in one step in the cycle of operations of said driving means;

55 Fig. 15 is a view of the mechanism as seen

from the right of Fig. 14 and turned at right angles relative thereto, certain parts being omitted;

Fig. 16 is a view similar to Fig. 14 but showing another step in the cycle of operation of the carrier rods and driving means therefor;

Fig. 17 is a view of the mechanism as seen from the left of Fig. 16 and turned at right angles relative thereto, certain parts being omitted;

Figs. 18, 20, 22 and 24 are views similar to Figs. 14 and 16 showing further steps in a cycle of operation of the carrier rods and driving means therefor;

Figs. 19 and 23 are views similar to Fig. 15 as seen from the right of Figs. 18 and 22, respectively;

Figs. 21 and 25 are views similar to Fig. 17, as seen from the left of Figs. 20 and 24, respectively;

Fig. 26 is a view similar to Fig. 2 of another form of carrier rod driving mechanism with a modified form of the invention applied thereto;

Fig. 27 is a view similar to Fig. 26 but with certain parts broken away;

Fig. 28 is a cross sectional view taken substantially along the line 28—28 of Fig. 26;

Fig. 29 is a cross sectional view taken along the line 29—29 of Fig. 26;

Fig. 30 is a cross sectional view taken substantially along the line 30—30 of Fig. 27 and having an element in back of the line of section appearing in dot-and-dash outline; and

Fig. 31 is a view similar to Fig. 30 but showing the parts in different positions relative thereto.

In the drawings and description, only the knitting machine parts necessary to a complete understanding of the invention have been specifically set forth; further information as to the construction and operation of other related, usual and well known knitting machine elements, mechanisms, etc., may be found in one or more of the following publications:

1. Pamphlet entitled—Full Fashioned Knitting Machines—published and copyrighted by the Textile Machine Works, Reading, Pennsylvania, in 1920.

2. Three catalogs entitled—The “Reading” Full-Fashioned Knitting Machine Parts Catalog—published and copyrighted by the Textile Machine Works, in 1929, 1935, and 1940, respectively.

3. Booklet entitled—The “Reading” High-Production Full-Fashioned Knitting Machine—which forms a supplement to the above noted 1940 parts catalog of the Textile Machine Works, and which booklet is a publication of the Textile Machine Works, and was copyrighted by the latter in 1940.

4. Pamphlet entitled—Knitting Machine Lectures—published by the Wyomissing Polytechnic Institute, Wyomissing, Pennsylvania, in 1935.

Referring to the drawings and more particularly Figs. 1, 9 and 13, I have shown a knitting machine to which a ringless attachment or carrier rod driving mechanism is applied and which comprises transverse end and center members 10 and 11 connected to each other by a front beam 12, a back beam 13, a front bed 14 and a center bed 16. The end and center frames 10 and 11 carry a cam shaft 17 for operating the various mechanisms of the machine. Mounted on the center bed 16 are brackets 18 in which are slidably mounted carrier rods 1 to 8, having yarn guide fingers for feeding yarn to the needles (not shown) of the machine. The car-

rier rods 1 to 8 are actuated or driven to feed yarn to the needles by means of an actuating device 22 carried by and frictionally engaged to a full-speed friction rod 21 of the machine.

The carrier rod actuating or driving mechanism 22 is of a selector type employed for reciprocating a plurality of carrier rods in recurring sequence and comprises a friction box housing 23, as shown in Figs. 2, 6 and 7, which is provided with the usual friction shoes (not shown) and a camming lever 26 for frictionally engaging or releasing the box from the friction rod 21. The housing 23 is supported in sliding relation on a usual half speed friction rod 27 of the machine and is provided with a pivoted arm 24 for engagement with dogs 20, one of which is shown in Figs. 6 and 7, on a speed reducing rod 25.

Cooperating with the friction box for reciprocating certain of the carrier rods, and more particularly carrier rods 1, 2 and 3 (Figs. 6 and 7), is a lever or selector element 28 which is slidably mounted on a square shaft 29, said lever 28 projecting from the shaft 29 and between projections 31 of the friction box 23 to be reciprocated with the friction box 23 by the friction rod 21. The shaft 29 has concentric end portions 30 by means of which the shaft is carried in brackets secured to the machine frame one of which is shown at 32 (Fig. 2), said shaft having collars 33 secured thereto at opposite sides of the bracket 32 for preventing axial movement of the shaft. The lever or element 28 is provided with long fingers or elements 36 and 38, and a short finger or element 37 for alternate engagement with dogs 41, 42 and 43 carried by the carrier rods 1, 2 and 3, in a manner hereinafter set forth.

The shaft 29 is rocked to engage the fingers 36, 37, and 38 with the dogs 41, 42 and 43 by a lever 44 secured to one end 39 of shaft 29 (Fig. 2) and which carries a cam follower 45 for engagement with a cam 46 (Figs. 10 and 11) carried by an auxiliary cam shaft 47 rotatably mounted in one of the brackets 32. A spring 51 connected between an extension 48 of the lever 44 (Figs. 6 and 7) and a pin 52 on the bracket 32, maintains the follower 45 on the lever 44 in engagement with the cam 46.

The shaft 47 and cam 46 are given a step-wise rotative movement by means of a ratchet wheel 53 secured to the shaft 47 and a pawl 54 (Figs. 2, 3 and 4) carried by one arm 55 of a lever 56 pivotally mounted on the shaft 47 between the ratchet wheel 53 and a hand wheel 57 secured to the shaft 47 for manually turning the same. The pawl 54 is maintained in engagement (Fig. 3) or out of engagement with the ratchet wheel 53 (Fig. 4) by an over-the-center spring 58, opposite ends of which are connected to the pawl 54 and lever 56, respectively. The lever 56 is given a rocking movement to turn the shaft 47 by a link 61, connected at one end to a second arm 60 of the lever 56 by a pin and toggle arrangement 62, and at its other end to a lever 63. The lever 63 is pivotally mounted on a bracket 64 (Fig. 9) carried on the back beam 13 and has a cam follower 66 pivotally mounted thereon for engagement with a cam 67 on the cam shaft 17 when the cam shaft is in the knitting position and with a concentric disk 68 when the cam shaft has been shifted to the right or narrowing position, as viewed in Fig. 1. A spring 71, connected to the lever 63 and to a bracket 70 on the front beam 12, maintains the cam follower 66 in engagement with the cam 67 or disk 68.

The shaft 47 is prevented from over-travel during its racking movement by a brake arrangement (Figs. 11 and 12) including a plate 72 having a friction disk 73, such as of leather, secured thereto as by rivets 74 and a disk 76, secured to the shaft 47. Projections 77 of the bracket 32 engage in notches 78 in the plate 72 to prevent the plate and friction disk 73 from rotating. The friction disk 73 is held in frictional engagement with the disk 76 by a series of springs 81, the amount of frictional engagement between the friction disk 73 and disk 76 being adjustable by means of lock nuts 82. The disk 76 is provided with notches 83 for engagement by a detent member 84 which is pressed toward the disk 76 by a spring 86 for holding the shaft 47 in proper angular position between racking movements of the shaft.

The reciprocating movements of the carrier rods 1 to 8 are controlled by end stops 87 carried by a carrier rod end stop nut 88 of a usual narrowing head mechanism N provided at both ends of the knitting machine. Also carried on the end stop nut 88 at each end of the machine is a carrier rod holding or rebound stop device, similar to that shown on pages 126 and 127 and 204 of the aforementioned 1935 parts catalog, to hold the idle carrier rods during operation of the active carrier rods. The holding or rebound stop device, as shown in Figs. 1 and 13, comprises in general a housing 91, secured to and movable with the end stop nut 88 in which are slidably mounted stop members 92, one for engagement with a dog 93 on each of the carrier rods 1 to 8, only carrier rods 3, 5 and 7 of which are shown having dogs 93 (Fig. 13). The stop members 92 are pressed toward the carrier rods by springs 94, the springs for the stop members for carrier rods 1 to 4 being shown in Fig. 13 and the springs for the stop members for the carrier rods 5 to 8 shown generally in Fig. 1. The stop members 92 are raised, to release the carrier rods 1 to 4 to permit the active carrier rods to be reciprocated across the knitting field, by an arm 95 secured to a lever 97 pivotally mounted on a shaft 98, the lower end of lever 97 being provided with a forked portion 101 which cooperates with a projecting portion 102 of a yoke member 103, also pivotally mounted on the shaft 98. The yoke member 103 is provided with a pin 104 for engagement with the upper end of a lever 106 which is pivotally mounted on a bracket 107 secured to the back beam 13, and carries a cam follower 108 for engagement with a cam 111 on the cam shaft 17. A spring 112 connected between the lever 106 and a bracket 113 on the back beam 13 maintains the cam follower 108 in engagement with the cam 111.

The stop members 92 for the carrier rods 5 to 8 are raised by an arm 114 (Fig. 1) carried by a lever 116, also pivotally mounted on the shaft 98, the lower end of lever 116 cooperating with a cam arrangement 117 carried on a plating bar 118 secured to the usual connecting bar (not shown) of the machine, this cam arrangement being similar to that shown in the aforementioned pages 126 and 127 of the 1935 parts catalog.

Each of the dogs 41, 42 and 43 are provided with a slot 119, a high portion 120 and a low portion 121 at the left side of the slot 119 and high and low portions 122 and 123, respectively, at the right side of the slot 119 by means of which each of the carrier rods 1, 2 and 3 are engaged and reciprocated in recurring sequence, high portions 120 all being on the front sides of

the dogs and high portions 122 on the rear sides thereof.

In operation with the carrier rods 1, 2 and 3 in the position of Fig. 14, in which carrier rods 1 and 2 are at the right against their respective end stops 87 and the carrier rod 3 is against its left end stop 87, the cam 46 actuates the lever 28 to engage the long finger 36 in the slot 119 of dog 42 and align the short finger 37, longitudinally of the carrier rods, with the right low portion 123 and the left high portion 120 of the dog 43 on the carrier rod 3, as shown in Figs. 14 and 15. Upon movement of the friction box 23 to drive the carrier rod 2 to the left, the short finger 37 passes over the right low portion 123 of dog 43. As the carrier rod 2 strikes its end stop 87 the short finger 37 engages the left high portion 120 on the dog 43 to press the carrier rod against its left end stop 87, so that the slot 119 in the dog 43 is in position to be engaged by the long finger 38 of lever 28. The lever 28 is then operated by the cam 46 to move the long finger 38 into the slot 119 of dog 43 (Fig. 16) and the short finger 37 into longitudinal alignment with the right high portion 122 of the dog 41 on the carrier rod 1. Upon movement of the friction box 23 to the right with carrier rod 3, the short finger 37 passes over the left low portion 121 (Figs. 18 and 19) of the dog 41 on the carrier rod 1 and presses against the right high portion 122 of the dog 41. The lever 28 is then operated by the cam 46 to move the long finger 36 into engagement with the slot 119 of dog 41 on the carrier rod 1, as shown in Fig. 18, and the low finger 37 is aligned, longitudinally of the carrier rods, with right low portion 123 (Figs. 18 and 19) and the left high portion 120 of the dog 42. Upon movement of the friction box 23 from right to left the low finger 37 passes over the right low portion 123 and presses against the left high portion 120 of the dog 42 on the carrier rod 2.

Figs. 20 to 25 are similar to Figs. 14 to 19 and together Figs. 14 to 25 show the position of the lever 28 during a complete yarn laying cycle of operation of the carrier rods 1, 2 and 3.

As shown in Figs. 14 to 25, long fingers 36 and 38 are employed to engage dogs 41, 42 and 43 on the carrier rods 1, 2 and 3, respectively, to drive the carrier rods to the right and left across the knitting field and the short finger 37 is utilized to engage the left high portion 120 or right high portion 122 of the idle carrier rod at the end of each yarn laying stroke to insure that the dogs on the idle carrier rods are in position to be engaged by one of the long fingers 36 or 38.

When it is desired to discontinue operation of the alternating carrier rods, the carrier rod connecting and releasing lever or element 22 is moved to an inactive position relative to the dogs on the carrier rods. For this purpose there is provided a cam member 124 (Figs. 6, 7, 8, 10 and 11), pivotally mounted on a hub portion 125 of the cam 46 (Fig. 11), and having a projection 126 which carries a pin 127 and a spring 128 connected between the pin 127 and a pin 129 carried in the bracket 32. The cam member 124 is adapted to engage the cam follower 45 on the lever 44 to turn the shaft 29 and lever 28 to move the fingers 36, 37 and 38 to an inactive position relative to the carrier rods. When it is desired to move the lever 28 to inactive position relative to the carrier rods, the cam member 124 is rotated manually in a counterclockwise direction

from the position shown in Fig. 6 to that shown in Figs. 7 and 8, the spring 128 maintaining a projection 131 on the cam member 124 in engagement with the pin 129 until again moved to the position of Fig. 6 by the operator.

When it is desired to again operate the friction box 23 and to move the fingers 36, 37 and 38 of lever 28 into the path of the dogs on the carrier rods 1, 2 and 3, the cam member is rotated to the position of Fig. 6. However, it is desirable to prevent engagement of the fingers 36 or 38 with an improper carrier rod to start the alternating sequence or to move the fingers to such position that no carrier rod is engaged, as sometimes occurs when the shaft 47 and cam 46 is accidentally rotated while the friction box is in disengaged position. For this purpose, there is provided an arm 132 carried by the cam member 124 and having a follower portion 140 for engagement with a cam 133 secured to the hub portion 125 of cam 46, as shown in Fig. 5. The follower portion 140 is maintained in engagement with the cam 133 by means of a spring 134 which is connected between a pin 135 on the arm 132 and a pin 137 on the projection 126 of said cam member 124 (Fig. 6). The arm 132 also has a cutaway portion 139 for purposes hereinafter set forth.

During operation of the box 23 to lay yarn to the knitting elements, the cam member 124 is positioned, as shown in Fig. 6, with the cam follower 45 on the cam 46 to cause the lever 28 to engage with the carrier rods 1, 2 and 3 in alternating sequence. When the alternating sequence of the carrier rods is to be discontinued, after the friction box 23 has completed a yarn laying stroke from left to right and the lever 28 operated to engage the long finger 36 with the dog 42 of the carrier rod 2, as shown in Figs. 14 and 15, the lever 28 is moved in a clockwise direction, as viewed in Fig. 2, to release the friction box from the friction rod 21, the pawl 54 is moved from its active position of Fig. 3, to its inactive position shown in Fig. 4, the lever 24 is moved out of the path of dog 20 on the rod 25 and the cam member 124 is turned from its position in Fig. 6 to its position in Fig. 8. At this time the follower portion 140 of the arm 132 is in engagement with a low portion 141 of cam 133, the parts remaining in this position until the alternating sequence is again to be resumed, whereupon movement of the cam member 124 back to its position of Fig. 6 will again engage the finger 36 in the groove 119 of dog 42 on the carrier rod 2. However, if for some reason the shaft 47 has been accidentally turned to a position in which the arm 132 is in engagement with the high point of cam 133, as shown in Fig. 7, at the time the carrier rods 1, 2 and 3 are to be alternately operated, the cutaway portion 139 of arm 132 is moved into such position relative to the pin 129 as to prevent the cam member 124 from being moved to its position of Fig. 6. Consequently, before the cam member 124 may again be moved to permit the lever 28 to move into active position relative to the carrier rod 2, the shaft 47 must be rotated to bring the low point 141 of cam 133 into engagement with the arm 132, as shown in Fig. 8.

A further form of carrier rod driving and selector mechanism is shown in Figs. 26 to 31 and comprises a carrier rod alternating attachment of the two lever type, an auxiliary cam shaft associated therewith for selectively connecting and releasing the carrier rods of the alternating

series, a cam lever for disengaging the attachment from the friction rod, a safety lever for preventing operation of the cam lever to engage the attachment to the friction rod when the auxiliary cam shaft is in such angular position as to prevent engagement of a carrier or to cause engagement of an improper carrier at the start of the alternating sequence and a cam on the auxiliary cam shaft for controlling the operation of the safety lever.

Referring to the Figs. 26, 27 and 28, a carrier rod alternating attachment 151, shown generally on pages 197 to 203, of the aforesaid 1940 parts catalog, comprises a frame member or friction box 152 having frictional engagement with the friction rod 21 through the usual friction shoes 153, a plate spring member 154, and a cam lever 156, pivotally mounted in a yoke member 157, for engaging the attachment to or disengaging it from the friction rod 21. The frame portion or friction box 152 also is provided with a portion 155 having sliding engagement with the half speed friction rod 27.

The frame member 152 has upright members or arms 153 between which are disposed levers or selector elements 161 and 162 rotatably mounted on a shaft 163 eccentrically carried on a shaft 164 rotatably mounted in the arms 153. The shaft 163 may be turned about the shaft 164 by means of a lever 166 which is secured to the shaft 163 and carries a detent member 167 adapted to engage an opening 168 in the shaft 164 (Fig. 28), in either one of two positions of the lever 166 for reasons hereinafter set forth. The levers 161 and 162 have extensions 171 and 172, respectively, spaced by bolts 175 having jam nuts 175A from extensions 173 and 174 of cam levers 176 and 177, respectively, which are also rotatably mounted on shaft 163 and alongside of levers 161 and 162, respectively. The cam levers 176 and 177 have cam followers 178 and 181, respectively, for engagement with cams 182 and 183, respectively, disposed between the arms 153, on an auxiliary cam shaft 184 and rotated therewith by pawl and ratchet means (not shown) operated from the connecting bar of the machine in a manner similar to that shown in the F. Autem Patent No. 2,219,733, issued October 29, 1940. Tension springs 186 connected between extensions 179 and 180 also on the levers 161, 176 and 162, 177, respectively, transmit a pull between them to maintain the extensions 171 and 172 normally as close to extensions 173 and 174 as permitted by bolts 175 and springs 187 connected between the levers 161 and 162 and the friction box 152 (Fig. 28) urge the levers 161 and 162 in the clockwise direction as viewed in Fig. 28 to maintain the followers 178, 181 in contact with the cams 182 and 183, respectively by the clockwise torque thereby transmitted to levers 176 and 177. Said bolts 175 in extensions 171 and 172 contact with extensions 173 and 174 to hold extensions 161 and 162 in the desired relation to the carrier rods 1, 2 and 3 which are to be driven thereby, jam nuts 175A holding bolts 175 in adjusted position. Owing to springs 186 and 187 the motions of followers 178 and 181 are transmitted through trains of parts which are yieldable irrespective of the direction of movement of levers 161 and 162, whereby no damage results in case any portion of either of said extensions strikes an obstruction, an occurrence which their manner of use renders quite possible.

Levers 161 and 162 have fingers or elements 188 and 191 (Fig. 28) for engagement with dogs

192 (Fig. 29) on the carrier rods 1, 2 and 3 and are operated by the cams 182 and 183 to alternately connect and release the carrier rods 1, 2 and 3 in a manner similar to that shown in the aforesaid Patent No. 2,219,733.

When it is desired to discontinue operation of the attachment 151 at the end of the last yarn laying stroke of the alternating attachment in which the carrier rod 1 is moved from left to right, the cam shaft 184 is operated to connect the levers 161 and 162 to the carrier rod 2. At this time the detent member 167 is withdrawn from the right side of the opening 168, in the shaft 164 and the lever 166 rotated in a counter-clockwise direction, as viewed in Fig. 28, to a position in which the detent member 167 is engaged in the left side of the opening 168, which action moves the levers 161 and 162 to inactive position relative to the dogs 192 on the carrier rods. Also at this time, the pawl and ratchet means on the auxiliary cam shaft is disabled to prevent further rotation of the auxiliary cam shaft and the cam lever 156 is moved to the position of Fig. 27, to release the attachment 151 from the friction rod 21. The attachment is maintained in this condition until the carrier rods 1, 2 and 3 are again to be alternately operated.

In order to prevent engagement of any carrier rod except carrier rod 2 at the start of the next sequential operation of the carrier rods, there is provided a cam 193 mounted on the shaft 184 to rotate in fixed relation with the cams 182 and 183. The cam 193 cooperates with a projection 194 of a lever 196 pivotally mounted on a pin or bolt 197 carried by a bracket 198 secured to friction box 152 as shown in Figs. 30 and 31. The lever 196 has a second projection 201, which overlies the path of movement of an end 200 of the cam lever 156 when it is in the position shown in Fig. 27, and a spring 202 connected between the lever 196 and one of the arms 158 biases the projection 194 toward the cam 193. A bracket 203 (Figs. 30 and 31) limits the counter-clockwise movement of the lever 196 if the spring accidentally becomes disconnected from the lever 196.

With this arrangement, when the cam lever 156 has been moved to the position shown in Fig. 27, and the pawl and ratchet mechanism (not shown) for the shaft 184 has been disabled to prevent rotation of the shaft while the alternating attachment is inactive, the projection 194 of lever 196 will be in engagement with a low part 204 of cam 193 and the projection 201 positioned out of the plane of movement of cam lever 156, as shown in Fig. 31, whereupon the cam lever 156 may be turned in a counterclockwise direction as viewed in Fig. 27, to reengage the friction box 152 to the friction rod 21, and when the lever 166 is turned again to its position of Fig. 28, to lower the levers 161 and 162, the levers will be in position to engage the dog 192 of the starting carrier rod to start the "ringless" knitting. However, if for some reason the shaft 184 and cam 193 are accidentally rotated to the position in which the projection 194 is in engagement with the high portion of cam 193, as shown in Fig. 30, the projection 201 of the lever 196 will be in the plane of movement of the cam lever 156, so that it cannot be moved from its position of Fig. 27 to reengage the friction box 152 to the friction rod 21 until the shaft 184 is again turned to engage the low part 204 of cam 193 with the lever 196.

Of course, the improvements specifically shown and described by which I obtain the said results, can be changed and modified in various ways without departing from the invention herein disclosed and hereinafter claimed.

I claim:

1. In a straight knitting machine, the combination with a plurality of yarn carrier rods, driving mechanism for said rods, and a selector mechanism comprising selector elements forming part of said driving mechanism and effective to connect the latter with the rods in determined order beginning with a selector element and a certain carrier rod, of means for rendering said driving mechanism ineffective until said selector element is in position to engage said certain carrier rod.
2. In a straight knitting machine having a plurality of yarn carrier rods, driving mechanism for said yarn carrier rods, selector means for said yarn carrier rods associated with said driving mechanism for operating the rods in predetermined order starting with a certain carrier rod, and means for rendering said driving mechanism ineffective when said starting yarn carrier rod to be operated is not in engaging position with respect to said selector means.
3. In a straight knitting machine having yarn carrier rods, mechanism including a friction box for driving said yarn carrier rods, a device for connecting said yarn carrier rods to and releasing them from said friction box starting with a certain carrier rod, and means for preventing operation of said friction box to drive said yarn carrier rods when said connecting and releasing device is not in cooperating relation with respect to said starting yarn carrier rod.
4. In a full-fashioned knitting machine having a yarn carrier rod, mechanism including a friction box for driving said yarn carrier rod, means for connecting said yarn carrier rod to and releasing it from said friction box, and means for preventing operation of said friction box to drive said yarn carrier rod when said connecting and releasing means is not in position to engage said yarn carrier rod.
5. In a full-fashioned knitting machine having a yarn carrier rod, driving mechanism for said yarn carrier rod having an element for connecting said yarn carrier rod to and releasing it from said driving mechanism, means for moving said carrier rod connecting element from active to inactive position when said connecting element is in a predetermined position relative to said yarn carrier rod and means for preventing return of said connecting and releasing element to active position relative to said yarn carrier rod when said connecting and releasing means is not in said predetermined position with respect to said yarn carrier rod.
6. In a knitting machine having yarn carrier rods, means for driving said yarn carrier rods comprising, a friction box, an element for connecting said yarn carrier rods to and releasing them from said friction box in predetermined sequence, an auxiliary cam shaft, cam means on said auxiliary cam shaft for operating said element to connect and release said carrier rods, means on said auxiliary cam shaft for moving said element from active to inactive position when said element is in a predetermined position relative to said carrier rods and means for preventing movement of said element from inactive to active position relative to said car-

rier rods when said element is not in said predetermined position with respect to said yarn carrier rods at the start of said predetermined sequence.

7. In a knitting machine having yarn carrier rods, means for driving said yarn carrier rods comprising, a friction box, an element for connecting said yarn carrier rods to and releasing them from said friction box in predetermined sequence, an auxiliary cam shaft, cam means on said auxiliary cam shaft for operating said element to connect and release said carrier rods, means on said auxiliary cam shaft for moving said element from active to inactive position when said element is in a predetermined position relative to said carrier rods, and means including a cam member on said auxiliary cam shaft for preventing movement of said element from inactive to active position relative to said carrier rod when said element is not in said predetermined position with respect to said yarn carrier rods at the start of said predetermined sequence.

8. In a knitting machine having yarn carrier rods, means for driving said yarn carrier rods comprising, a friction box, means associated with said box including an element for connecting said yarn carrier rods to and releasing them from said friction box in predetermined sequence, an auxiliary cam shaft, means including a cam on said auxiliary cam shaft for controlling operation of said element to connect and release said carrier rods, means on said auxiliary cam shaft for moving said element from active to inactive position when said element is in a predetermined position relative to said carrier rods and means including a cam element on said auxiliary cam shaft and a cam follower member cooperating with said cam element for preventing movement of said carrier rod connecting and releasing element from inactive to active position when said element is not in said predetermined position with respect to said yarn carrier rods at the start of said predetermined sequence.

9. In a knitting machine having yarn carrier rods, a main cam shaft, means for driving said carrier rods comprising, a friction box, means associated with said friction box including an element for connecting said yarn carrier rods to and releasing them from said friction box in predetermined sequence, an auxiliary cam shaft, means including a cam on said main cam shaft for operating said auxiliary cam shaft, cam means on said auxiliary cam shaft for operating said element to connect and release said carrier rods, means on said auxiliary cam shaft for moving said carrier rod connecting and releasing element from active to inactive position when said connecting and releasing element is in a predetermined position relative to said yarn carrier rods and means including a cam element on said auxiliary cam shaft and a cam follower member cooperating with said cam element for preventing movement of said carrier rod connecting and releasing element from inactive to active position when said element is not in said predetermined position with respect to said yarn carrier rods at the start of said predetermined sequence.

10. In a knitting machine having yarn carrier rods, a main cam shaft, means for driving said carrier rods comprising a friction box, means associated with said friction box including an element for connecting said yarn carrier rods to and releasing them from said friction box

in predetermined sequence, an auxiliary cam shaft, cam means on said auxiliary cam shaft for operating said element to connect and release said carrier rods, means including a cam on the main cam shaft for operating said auxiliary cam shaft, means on said auxiliary cam shaft for moving said carrier rod connecting and releasing element from active to inactive position when said connecting and releasing element is in a predetermined position relative to said yarn carrier rods and means for preventing movement of said carrier rod connecting and releasing element from inactive to active position when said connecting and releasing means is not in said predetermined position with respect to said yarn carrier rods at the start of said predetermined sequence.

11. In a knitting machine having yarn carrier rods, a main cam shaft, means for driving said carrier rods comprising a friction box, means associated with said friction box including an element for connecting said yarn carrier rods to and releasing them from said friction box, an auxiliary cam shaft, cam means on said auxiliary cam shaft for operating said carrier rod connecting and releasing element, means including a cam on the main cam shaft for operating said auxiliary cam shaft, means on said auxiliary cam shaft and independently movable relative thereto for moving said carrier rod connecting and releasing element from active to inactive position when said connecting and releasing element is in a predetermined position relative to said yarn carrier rods, a stop member for limiting the movement of said independently movable means and means including a cam rotatable with said auxiliary cam shaft, a follower member for cooperating with said cam member, said follower member cooperating with said cam member and said stop member to prevent movement of said carrier rod connecting and releasing element from inactive to active position when said element is not in said predetermined position with respect to said yarn carrier rods.

12. In a full-fashioned knitting machine having yarn carrier rods, means for driving said yarn carrier rods, comprising a friction rod, a friction box, means for connecting said yarn carrier rods to and releasing them from said friction box alternately in predetermined sequence, means for engaging said friction box to and disengaging it from said friction rod when said connecting and releasing means is in a predetermined position relative to said yarn carrier rods in said predetermined sequence, and means for preventing engagement of said friction box to said friction rod when said yarn carrier rod connecting and releasing means is not in said predetermined position with respect to said yarn carrier rods to be connected in said predetermined sequence.

13. In a full-fashioned knitting machine, the combination of a group of carrier rods, a reciprocating friction box rod, a friction box on said rod, a lever adapted to selectively connect said carrier rods to said friction box, a pivoted member on which said lever is mounted, said lever being adapted and arranged to follow the movements of said box, a cam shaft having step-by-step rotative movement and having a cam fixed thereon arranged to determine the position of said lever to select said carrier rods for movement, a normally stationary hand operated cam member pivoted on said step-by-step shaft and adapted when in one position to hold said lever

out of contact with said cam and to prevent connection between said lever and said carrier rods and in its other position to permit operation of said lever by said cam for selecting said carrier rods, means for holding said manually operated member in one position or the other, a latch member pivoted on said manually operated member, and a second cam fixed on said step-by-step cam shaft and adapted to hold said latch member inoperative or to permit it to latch said manually operated member in position to prevent connection of said lever to said carrier rods depending on the angular position of said cam shaft.

14. In a full-fashioned knitting machine, the combination of a group of carrier rods, a friction box rod having a friction box thereon, means whereby said box may be connected to said rod, a cam shaft, means to give said cam shaft a step-by-step rotative movement, a cam splined to said shaft and arranged to move with said friction box, a pair of levers pivotally mounted with respect to said friction box and arranged to move therewith for connecting said box to said carrier rods in predetermined sequence, means whereby said cam on said step-by-step shaft moves said levers into position to operate said carrier rods, means associated with the pivot of said levers whereby said levers may be thrown into position in which said cam does not act thereon and in which said levers are out of driving position with respect to all said carrier rods, a second cam on said step-by-step shaft, and means cooperating with said second cam and adapted when said first cam is inactive with respect to said levers to either permit or prevent the operation of the means whereby the friction box may be connected to its friction box rod depending on the angular position of said step-by-step shaft.

15. In a full-fashioned knitting machine having a yarn carrier rod, means for driving said yarn carrier rod comprising, a friction rod, a friction box, means on said friction box for connecting said yarn carrier rod to and releasing it from said friction box, means for engaging said friction box to and disengaging it from said friction rod when said connecting and releasing means is in a predetermined position relative to said yarn carrier rod and means for preventing said engagement of said friction box to said friction rod when said carrier rod connecting means is not in said predetermined position with respect to said yarn carrier rod.

16. In a full-fashioned knitting machine having yarn carrier rods, means for driving said carrier rods comprising a friction rod, a friction box, means on said friction box for connecting said carrier rods to and releasing them from said friction box, a cam lever carried by said friction box for engaging said friction box to and disengaging it from said friction rod when said connecting and releasing means is in a predetermined position relative to said yarn carrier rods and means for preventing movement of said cam lever from said disengaged position to said engaged position to engage said friction box to said friction rod when said connecting and releasing means is not in said predetermined position with respect to said yarn carrier rods.

17. In a full-fashioned knitting machine having yarn carrier rods, means for driving said carrier rods comprising a friction rod, a friction box, a pair of elements for alternately connecting said yarn carrier rods to and releasing them from

said friction box in predetermined sequence, a cam lever for engaging said friction box to and disengaging it from said friction rod when said connecting and releasing elements are in a predetermined position relative to said yarn carrier rods, an auxiliary camshaft, cam means on said auxiliary camshaft for operating said elements to connect and release said carrier rods, and means for preventing movement of said cam lever from said disengaged position to said engaged position to engage said friction box to said friction rod when said carrier rod connecting and releasing elements are not in said predetermined position with respect to said yarn carrier rods at the start of said predetermined sequence.

18. In a full-fashioned knitting machine having yarn carrier rods, means for driving said carrier rods comprising a friction rod, a friction box, a pair of elements for alternately connecting said 20 yarn carrier rods to and releasing them from said friction box in predetermined sequence, an auxiliary camshaft, cam means on said auxiliary camshaft for operating said elements to connect and release said carrier rods, a cam lever for engaging said friction box to and disengaging it from said friction rod when said pair of carrier rod connecting and releasing elements are in a predetermined position relative to said yarn carrier rods and means including a cam on said auxiliary camshaft for preventing movement of said cam lever from said disengaged position to said engaged position to engage said friction box to said friction rod when said pair of carrier rod connecting and releasing elements are not in said predetermined position with respect to said yarn carrier rods at the start of said predetermined sequence.

19. In a knitting machine having yarn carrier rods, means for driving said carrier rods comprising a friction rod, a friction box, means carried by the box including a pair of elements for alternately connecting said yarn carrier rods to and releasing them from said friction box in predetermined sequence, an auxiliary camshaft, cam 40 means on said auxiliary camshaft for operating said elements to connect and release said carrier rods, a cam lever for engaging said friction box to and disengaging it from said friction rod when said pair of elements are in a predetermined position relative to said yarn carrier rods, and means including a cam on said auxiliary camshaft and a lever adapted to be positioned in the plane of movement of said cam lever by said cam for preventing movement of said cam lever from said disengaged position to said engaged position to engage said friction box to said friction rod when said pair of elements are not in said predetermined position with respect to said yarn carrier rods at the start of said predetermined sequence.

20. In a straight knitting machine, the combination with a plurality of yarn carrier rods, driving mechanism for said rods comprising a reciprocating member and a selector mechanism including at least one selector element and effective to connect said member with the rods in a determined order beginning with a selector element and a certain carrier rod of means for preventing a connection between said member and any of said carrier rods except when the selector mechanism is in position to engage properly with said certain rod.

21. In a straight knitting machine, the combination with a plurality of yarn carrier rods, driving mechanism for said rods comprising a recip-

rotating member and a selector mechanism including at least one selector element and effective to connect the latter with the rods in a determined order beginning with a selector element and a certain carrier rod of means responsive to the relative position of said selector mechanism

and said rods for preventing a connection between said member and any of said carrier rods operable only when said selector mechanism is out of the position to engage properly with said 5 certain rod.

GOTTLOB BITZER.
